CALK FOR ANTI-SKID TIRE CHAINS

Arthur M. Haynes, St. Catharines, Ontario, Canada, assignor to Columbus McKinnon Chain Corp., Tonawanda, N. Y., a corporation of New York

Application October 24, 1940, Serial No. 362,641

6 Claims. (Cl. 152—245)

My invention relates in general to calks for anti-skid chains and particularly to anti-skid cross chain links of the curb type, which have their ends joined by welding.

It is well known to those skilled in the art that in cross chains of this type, the raised curved surfaces of the link which contact with the pavement wear very rapidly; and, when in this condition they readily break under the slightest added strain.

The principal object of my invention has been to provide a calk for the links of an anti-skid cross chain that shall project above the normal curved contact surfaces of the link and which will take a substantially large part of the wear while the link is in use.

Another object has been to provide a calk which may be held in engagement with the chain link by being inserted between the sides of the chain link.

A further object has been to provide a method of assembling whereby the calks may be held in place within the link by engagement of the side walls therewith, the side walls being forced inwardly in the act of fastening the calk in place within the link.

Moreover, by reason of the method of assembling of my invention, it is possible to properly harden the calk so that it may be more resistant to wear, while permitting the link to be hardened only sufficiently to produce maximum toughness.

Furthermore, my calk is held in place within the link only by means of the clamping engagement of the sides of the link with the calk.

Moreover, the calk of my invention is so proportioned in respect to the width of the link that it does not at any point extend beyond the outer contour thereof.

Moreover, it has been an object to provide a single-piece calk which shall extend across between the link from one side thereof to the other, and thereby provide struts between the sides of the link.

The above objects and advantages have been accomplished by the devices shown in the accompanying drawing, of which:

Fig. 1 is a plan view of one form of my invention applied to a link of an anti-skid cross chain.

Fig. 2 is a side elevation thereof.

Fig. 3 is a perspective view of the form of calk of Figs. 1 and 2.

Fig. 4 is an end elevation thereof.

Fig. 5 is a plan view of a modified form of calk.

Fig. 6 is a side elevation thereof.

Fig. 7 is a perspective view of the form of calk of Figs. 5 and 6.

Fig. 8 is an end elevation thereof.

Fig. 9 is a plan view of another modified form of calk applied to a link.

Fig. 10 is a side elevation thereof.

Fig. 11 is a perspective view of the calk of Figs. 9 and 10.

Fig. 12 is an end elevation thereof.

Fig. 13 is a plan view of still another form of calk in position within a link.

Fig. 14 is an end elevation of the same.

Fig. 15 is a perspective view of the form of calk of Figs. 13 and 14.

Fig. 16 is an end elevation thereof.

Fig. 17 is a plan view of a link and a calk in the process of being assembled.

Fig. 18 is a side elevation showing a number of assembled links in position of use, having the form of calk of Figs. 1 to 4, inclusive.

In general, my invention relates to a calk which is preformed and provided with grooves in its sides for engagement with the sides of the carrying link. The calk may take various forms, as indicated in the drawing, each form being provided with the grooves just mentioned.

Reference is now to be had particularly to the form of calk shown in Figs. 1 to 4, inclusive, where the calk 20 is substantially Z-shape in cross-section, thus providing three struts 21, 22 and 23.

The calk is substantially uniform in cross-section and is of such a height as to extend somewhat beyond the curved surfaces 24 and 25 of the link 26 by which it is carried, as shown in Fig. 2. As shown in the drawing, the calk extends through the interior of the link and is located between the sides 30 and 31 thereof. The calk is formed with free edges 32 and 33 as well as curved edges 36 and 37 at the points of juncture of the struts 21 and 22, and 22 and 23. Grooves 34 and 35 are formed, respectively, in the edges 32 and 33 and, likewise, grooves 40 and 41 are formed in the edges 36 and 37, respectively, for the reception of the sides 30 and 31 of the link. The pairs of grooves 34 and 40, and 35 and 41 are so angularly arranged with respect to each other that they will register with and engage the inclined sides 30 and 31 of the curb link 26, as clearly shown in the drawing. The distance between the grooves 34 and 41, and 40 and 35 is such that when the sides 30 and 31 of the link are in their normal positions, as shown in the drawing, the calk will be firmly held in place by the clamping engagement of said sides. The width of the calk is

such that there will be sufficient extension over the sides of the link to anchor the calk within the same. It is desirable, however, that the calk does not extend beyond the outer boundaries of the link sides although it may do so if desired. As shown in most of the forms of my invention, the struts of the calk engage the inner peripheries of the link sides.

In carrying out my invention the links of the chain are preferably initially formed, as shown in Fig. 17, so that there is sufficient space between the sides to permit the passage of the calk, which is brought to a position in the link where its recesses will register with the sides, after which such sides are forced toward each other and the link is thus bent into the final shape, as for instance that shown in Fig. 1. During such bending action, the sides of the link will engage and be forced into the calk recesses and thereby firmly hold the calk in position without further fastening means.

In the form of invention shown in Figs. 5 to 8, inclusive, the calk 45 is substantially U-shaped in cross-section when viewed from the side (see Fig. 6). It is provided with two leg portions 46 and 50 which are joined by a flat portion 51 arranged at the tire engaging side of the link 26. The leg portions are each provided with oppositely arranged recesses 52, 53 and 54, 55. The leg portions 46 and 50 each have a road-engaging wearing surface 56 which extends preferably the full width of the link as shown in Fig. 5. The flat or tire engaging portion 51 is preferably of a width sufficient to extend across and engage sides 30 and 31 of the link. When this calk is assembled with the link, it is necessary that the sides of the link be spaced only sufficiently to permit the passage of the portion 51 therebetween. Otherwise, the assembling is the same as hereinbefore described.

In the form of invention shown in Figs. 9 to 12, inclusive, the calk 60 is substantially rectangular in cross-section, having an opening 61 and side walls 62 and 63, connected by means of strut forming walls 64 and 65. As shown in Fig. 12, 45 the side members 62 and 63 are each formed, respectively, with a groove 66 and 70 for engagement, respectively, with the sides 30 and 31 of the link 26. The road engaging surface of this calk is preferably provided with serrations or teeth 72 so as to increase the gripping ability of the calk.

In the form of invention shown in Figs. 13 to 16, inclusive, the calk 73 is preferably V-shaped in cross-section and is formed similarly to the Z-shaped form of invention of Figs. 1 to 4, inclusive. This calk is therefore provided with two leg portions 74 and 75 which form struts extending across between the sides 30 and 31 of the link 26. The face 76 of each of the struts is formed with a groove 80 and the surface 81 at the junction of the struts 74 and 75 is also formed with a groove 82. The grooves 80 are engageable with the side 31 of the link and the groove 82 is engageable with the side 30 of the link.

Obviously, the calks of the last two described forms of my invention are assembled with the links in a manner similar to that hereinbefore described.

In Fig. 18, a number of links 26 are shown assembled in a cross chain, the calks there shown being substantially the same as those illustrated in Figs. 1 to 4, inclusive. In this figure the circle 83 shown in broken lines represents the contour of the tire and the straight line 84, represented

in broken lines, indicates the surface of the roadway over which the tire bearing the chain is traveling. From this figure it will be obvious that the surfaces 24 of the link are held out of contact with the road surface 84, and that the road engaging surface of the calk 22 will take the wear and abrasion resulting from contact with the road whereby the life of the links of the cross chain will be greatly increased.

While I have shown a number of forms of calks, it is obvious that my invention is applicable also to other forms of calks such as will provide struts extending across from one side of the link to the other, and which may be held in position by means of the engagement of the sides of the link with grooves formed in the strut members of such calks.

Furthermore, while I have shown my calk assembled in a link formed as shown in Fig. 17, it is obvious that the links may be initially formed as shown in the other figures and the calk so proportioned that it may be forced in between the sides of the link, causing them to spring outwardly to admit the calk, after which they will spring back again into the recesses of the calk thereby firmly holding the same in place.

Having thus described my invention, what I claim is:

1. A calk for individual links of an anti-skid chain, said calk being disposed within the link and formed with a plurality of interspaced struts adapted to extend across between the sides of the link, said struts being so formed as to extend through the link and to project from opposite faces thereof, and said struts having preformed grooves in its opposite sides for registration and close-fitting engagement with said link sides.

2. A calk for individual links of an anti-skid chain, said calk being disposed within the link and formed with a plurality of interspaced struts adapted to extend across between the sides of the link, said struts being so formed as to extend through the link and to project from opposite faces thereof, said calk having an integral member connecting said interspaced struts, and said struts having preformed grooves in their opposite sides for registration and close-fitting engagement with said link sides.

3. A calk for individual links of an anti-skid chain, said calk being disposed within the link and formed with a plurality of interspaced, parallel struts adapted to extend across between the sides of the link, said struts being so formed as to extend through the link and to project from opposite faces thereof, and said struts having preformed grooves in its opposite sides for registration and close-fitting engagement with said link sides.

4. A single-piece calk for welded anti-skid chain links, said calk comprising a plurality of interspaced struts and an integral member connecting said struts, said calk engaging the link and having its struts adapted to extend across between the sides of the link, said calk being so formed as to extend through the link and to project from opposite faces thereof, and said struts having preformed grooves in their opposite sides for registration and close-fitting engagement with the link sides.

5. The combination with a welded anti-skid chain link of the curb type, of a single-piece calk, comprising a plurality of interspaced struts and an integral connecting member, said struts projecting from opposite faces of the link and having preformed grooves in the opposite sides

thereof for registration and close-fitting engagement with the surfaces of the inner perimeter of the sides of the link.

6. A calk for welded anti-skid chain links, said calk being disposed within the link and adapted to extend across between the sides of the link, said calk being so formed as to extend through the link and to project from opposite faces

thereof, and said calk being preformed and having grooves in its opposite sides shaped to conform substantially throughout their lengths to the link sides, said grooves being in close-fitting engagement with said link sides and held therebetween only by the springing engagement of said link sides.

ARTHUR M. HAYNES.
